UNITED STATES PATENT OFFICE

2,116,396

ELECTRIC SWITCH OPERATING APPARATUS

Charles H. Hill and Arvid E. Anderson, Drexel Hill, Pa., assignors to General Electric Company, a corporation of New York

Application May 22, 1934, Serial No. 726,887

5 Claims. (Cl. 200—89)

Our invention relates to electric switches of that type in which the switch is tripped to open circuit position in response to an abnormal condition in the circuit controlled thereby and is automatically reclosed after being tripped open.

Certain forms of switches of this type heretofore constructed have employed a collapsible mechanism connecting the switch with the operating device therefor by the collapse of which mechanism the switch would be permitted to open independently of the operating device, the construction of the mechanism being such that it would subsequently reset itself automatically in readiness for another switch closing operation. The mechanism also was provided with a circuit controller for reenergizing the operating device when the switch moved to open circuit position in response to an abnormal condition. In certain forms of such apparatus the difficulty has arisen that the operating device has been reenergized before the resetting operation of the mechanism was completed with the result that the switch failed to reclose.

It is one object of our invention to provide an improved switch operating apparatus which will avoid this difficulty. Another object of our invention is the provision of apparatus which will avoid this difficulty where the switch is provided with means for causing a repeated reclosing of the switch at predetermined intervals for a predetermined number of times should the abnormal condition persist.

Our invention will be better understood from the following description taken in connection with the accompanying drawings, and its scope will be pointed out in the appended claims.

Referring to the drawings Figs. 1, 2 and 3 illustrate the switch and operating mechanism therefor in three different positions. Figs. 4, 5 and 6 show the controlling device of the mechanism drawn to a larger scale and corresponding in position respectively to its positions in the preceding figures.

We have chosen to illustrate our invention as actuated by a motor driven centrifugal device which device, it will be understood, is of such a character that it will continue to rotate after the switch has been closed thereby and the motor deenergized because of the inertia of the moving parts, until finally it comes to rest by reason of the friction and windage thereof.

Referring to Figs. 1, 2 and 3, the switch is shown in part only being represented by the fixed contacts 1 and the cooperating movable contact 2, one of the leads 3 to the fixed contacts being

provided with the usual winding 4 which connects with the relay 5 for the operation of the usual switch tripping means. The operating rod 7 of the switch connects with the lever 8 which in turn connects through the toggle 9 with the collapsible mechanism comprising links 10 and 11 which links are pivoted together at 12 and are retained in alignment as shown by Figs. 1 and 3 by means of the latch 13, this latch being pivoted to link 10 and arranged to be tripped to disengage member 11 by the tripping magnet 14 which is connected to be controlled by relay 5. Member 11 at its free end is pivoted to the lever 16 one end of which comprises a counter-weight while the other end is pivotally connected with 15 the centrifugal mechanism comprising the fly-balls 17 and connecting linkage 18, the centrifugal mechanism being rotated by the electric motor 19.

The lever 8 has an arm carrying the movable contact 21 of an auxiliary switch whose rear contacts 22 are in the circuit of the tripping magnet 14 and whose front contacts 23 are in the circuit of relay 24 to be described later. At 25 we have shown a fluid reclosing device whose internal construction is illustrated by Figs. 4, 5 and 6 and which in the position illustrated by Fig. 3 is adapted to close a circuit connected with the source of supply 26 through the switch 21, 23 and the winding of relay 24. The latter relay 30 when energized connects the fixed contacts 27 so as to seal in the winding and it also connects the fixed contacts 28 so as to close the circuit of motor 19 which receives energy from the same source 26. By means of the hand switch 29 the relay 24 may be manually actuated and through the hand switch 30 the tripping magnet 14 may be manually actuated.

As shown in Figs. 4, 5 and 6, the reclosing device 25 comprises a closed receptacle having a 40 transverse partition therethrough dividing it into the chambers 32 and 33, the device being partially filled with a suitable conducting liquid such, for example, as mercury. In chamber 33 is the receptacle 34 in which are the two conductors 35 and 36, the latter being insulated except at its upper end whereby the fluid contained in the device will electrically connect the two conductors only after the receptacle 34 has been substantially filled. The partition across the device is 50 provided with the two tubes 38 and 39 forming restricted passages through which the fluid may pass at a predetermined rate. Thus when the device is in the position shown by Fig. 6 the fluid in chamber 32 runs through the pipe 38 into the 55

receptacle 34, and when the device is inverted to the resetting position shown in Fig. 4 the fluid, after being dumped from receptacle 34, returns to chamber 32 through the other tube 39. The device 25 is disclosed and claimed in the copending application of Arvid E. Anderson, Serial No. 704,653, filed December 30, 1933, which became Patent No. 2,055,327 on September 22, 1936.

The device 25 is pivotally mounted on the transverse axis 40 and is provided with the arm 41 by which it is partially rotated on that axis. The device is arranged to have its angular position controlled by the position of the switch operating mechanism. Connection between the arm 41 of device 25 and the link 10 includes the link 42, the bellcrank 43, and the rod 44. On one end of bellcrank 43 is pivoted the block 45 which is arranged to slide on rod 44 and engaging opposite sides of this block and surrounding the rod 44 are the two coil springs 46 and 47. Spring 46 is retained by the head 48 on the lower end of the rod, and spring 47 is retained by the block 57 slidably mounted on the rod. The latter block has the transverse pin 49 therein which engages in a slot in the latching lever 50. The opposite end of this lever is arranged to engage a projection on the link 51 pivoted at 52 whose lower end pivotally connects with the link 53. Spring 54 serves to resiliently retain link 51 against the stop 55. Link 53 is slotted at its opposite end and engaging in this slot is the pin 56 projecting from lever 16.

The operation of the above-described apparatus is as follows. Assuming the switch and the operating mechanism therefor to be in the closed circuit position illustrated by Fig. 1, should an abnormal condition such as a short circuit occur on the line controlled by the switch, relay 5 would be operated in response thereto closing the circuit of tripping magnet 14 to release the latch 13 whereby the collapsible connection comprising members 10 and 11 would move to the position shown by Fig. 2 to allow the switch to drop to its open circuit position. The switch thus would be tripped free of the centrifugal operating mechanism. Unless the centrifugal apparatus is rotating at that time the lever 16 by reason of its weight will thereupon move to the position shown by Fig. 3, in which position the collapsible mechanism comprising members 10 and 11 will reset itself to its extended or non-collapsed condition as shown in Fig. 3, the latch 13 dropping over the end of link 11 to the position shown in that figure. The device 25 by reason of its connection with the link 10 now is retained in its upright position as shown in Fig. 3 in which position the fluid contained therein runs through pipe 38 into the receptacle 34 which in a predetermined time, that may be several seconds, becomes filled with the liquid to the point where the terminals 35 and 36 are electrically connected thereby. The circuit thus is closed through the device 25, switch 21, 23 and the winding of relay 24. The energization of this relay closes the sealing circuit thereof and also closes the circuit of the motor 19 whereupon the centrifugal mechanism is started rotating. When this mechanism reaches sufficient speed the lever 16 is rotated in a counterclockwise direction from the position shown in Fig. 3 to that of Fig. 1, thus moving the switch to closed circuit position as shown by Fig. 1. Since device 25 now is in its inverted position, the fluid no longer is retained by the receptacle 34, hence it no longer connects terminals 35 and 36 and since

switch 21, 23 is no longer closed, relay 24 is de-energized thereby opening the circuit of motor 19.

If the aforementioned abnormal condition on the line controlled by the switch has been cleared in the meantime, the switch will remain closed. However, should the abnormal condition persist the tripping magnet 14 will again be energized to cause the switch again to be tripped to the open circuit position shown in Fig. 2. Because of the inertia of the motor armature and the flyballs, the centrifugal device will continue to rotate for sometime after the switch has reached its closed position, regardless of whether it remains closed, and the motor has been deenergized by the release of relay 24 and this continued rotation of the centrifugal device will maintain lever 16 in the position shown by Fig. 2 preventing the resetting of links 10 and 11. While these links are in this collapsed condition, see Fig. 2, the reclosing device 25 is retained in its horizontal or intermediate position by reason of the latch comprising the lever 50 and the cooperating projection on link 51. As long as device 25 remains in this intermediate position the fluid therein does not pass the partition in the device, hence the device remains inactive. Receptacle 34 is empty since the device 25 reached the inverted position during the closing operation. When the speed of rotation of the centrifugal device decreases to the point where it is no longer able to retain lever 16 in the position shown in Fig. 2 the heavy end of this lever causes the lever to rotate clockwise to the position shown by Fig. 3 which allows the collapsible links 10 and 11 to reset. By this movement of lever 16, the pin 56 therein by engaging the end of the slot in link 53 moves link 51 against spring 54 and releases the latch 50, whereupon spring 47 causes the device 25 to rotate counterclockwise to the position shown by Fig. 3. The fluid in the chamber 32 of this device now begins to pass through tube 38 into receptacle 34 as before and after a predetermined time will cause a reenergization of the motor again to close the switch in the manner already described. It will thus be seen that as long as the centrifugal mechanism is rotating in response to a previous energization at a speed sufficient to retain lever 16 in the position shown by Figs. 1 and 2, the device 25 is retained in an inoperative position. That is, the circuit of the motor is not closed thereby until the speed of the centrifugal mechanism falls to such a low value that the switch operating apparatus can reset itself.

Inasmuch as the flow of fluid into chamber 32, see Fig. 4, is restricted by the size of the opening of the tube 39, all of the fluid will not have time to return to chamber 32 and after the apparatus has reclosed a certain number of times within a predetermined length of time, there will be an insufficient amount of fluid in chamber 32 to fill the receptacle 34. Thus if the abnormal condition on the line persists indefinitely, the switch will reclose only a predetermined number of times after which no further effort will be made by the switch to close the circuit. Each time the device 25 is moved to the intermediate position shown by Figs. 2 and 5 the fluid which has not yet returned to chamber 32 remains in chamber 33, the intermediate position thereby being an inoperative position in which the device is held until the speed of the centrifugal appa-

ratus has reduced to such a value that the mechanism can reset.

We have chosen the particular embodiment described as illustrative of our invention and it will be apparent that various modifications may be made without departing from the spirit and scope of our invention which modifications we aim to cover by the appended claims.

What we claim as new and desire to secure by Letters Patent of the United States is:

- 10 1. A reclosing circuit breaker comprising a main switch, a motor driven centrifugal operating device therefor, a latch controlled collapsible connection between said switch and said device, said connection being constructed to reset itself in non-collapsed condition when the speed of the device decreases to a predetermined minimum, a pivotally mounted mercury time delay switch having an operative and an inoperative position for controlling said motor and means operative to hold said time delay switch in its inoperative position when said connection is collapsed and to move the same into its operative position in response to the resetting of said connection.
- 20 2. A reclosing circuit breaker comprising a main switch, a motor driven centrifugal operating device therefor, a latch controlled collapsible connection between said switch and said device, said connection being constructed to reset itself in non-collapsed condition when the speed of the device decreases to a predetermined minimum, a pivotally mounted mercury time delay switch for controlling said motor having an operative and an inoperative position, and mechanism connecting said time delay switch with said connection operative to retain the time delay switch in its inoperative position when the main switch is open and said connection is collapsed and to move the time delay switch to its operative position when the connection subsequently becomes reset.

3. A reclosing circuit breaker comprising a main switch, a motor driven centrifugal operating device therefor, a latch controlled collapsible connection between said switch and said device, said connection being constructed to reset itself in non-collapsed condition when the speed of the device decreases to a predetermined minimum, a pivotally mounted mercury time delay switch for controlling said motor having an operative position, an inverted position and an intermediate inoperative position, means for moving said time delay switch to its operative position when the main switch is open and said connection is reset and for moving the same to its inverted position when the main switch is closed and the connection is reset and means for retaining the device in its intermediate position while the switch is open and the connection is collapsed.

4. A reclosing circuit breaker comprising a main switch, a motor driven centrifugal operating device therefor, an auxiliary switch for controlling said motor, means tending to move said auxiliary switch to closed circuit position in response to a tripping open of said main switch, and means operative to restrain said means if the centrifugal device has a speed greater than a predetermined value.

5. A reclosing circuit breaker comprising a main switch, a motor driven centrifugal operating device therefor, an auxiliary switch for controlling said motor, means tending to move said auxiliary switch to closed circuit position in response to a tripping open of said main switch, and means controlled by said centrifugal device for restraining said means until the speed of said device shall have decreased to a predetermined value.

CHARLES H. HILL.
ARVID E. ANDERSON. 40
